UNITED STATES PATENT OFFICE.

RALPH LEONARD ASPDEN, OF CHORLEY, ENGLAND.

VARIABLE CONDENSER.

Application filed May 29, 1926; Serial No. 112,546, and in Great Britain May 7, 1925.

This invention relates to variable condensers as used in wireless and other instruments and has for its object to provide an improved construction and arrangement 5 of condenser which is particularly adapted to enable the tuning of several circuits to be effected from one control member in a simple manner.

My invention comprises a variable condenser in which the fixed and moving elements are arranged so that the capacity of the condenser is changed from minimum to maximum more than once in each half revolution of the moving elements.

15 My invention further comprises a variable condenser which consists of fixed and moving plates having peripheral gaps or slots and inwardly extending tongues, gaps and tongues coming into alignment more than 20 once in each half turn of the moving plates.

25 My invention further comprises the combination with a variable condenser as before referred to, of one or more condensers or variometers connected to said variable condenser either direct or through gearing.

Referring to the accompanying sheets of explanatory drawings:—

Figure 1 is a sectional view and Figure 2 an end view looking from right to left of 30 Figure 1 of one of my improved condensers coupled to an ordinary condenser for tuning two circuits from one control member.

35 Figures 3 and 4 are detail views of one construction of the fixed and movable plates of my improved condenser.

The same reference letters in the different views indicate the same parts.

The two condensers illustrated in Figure 1 are arranged in the ordinary known 40 manner with alternating fixed and moving plates, *a* and *c* indicating fixed plates and *b* and *d* moving plates. The lower condenser *e* is of usual construction but in the condenser *f* at the top side of Figure 1, the

45 plates are so constructed that the capacity of the condenser is changed many times during each half turn of the condenser *e*. The construction of the plates is shown in Figures 3 and 4. It will be seen that the fixed 50 plates, one of which is shown in Figure 3, have tongues *g* projecting radially inwards from the plate periphery whilst the moving plates, one of which is shown in Figure 4, have radial gaps or slots *h*. The fixed

55 plates are slightly larger in diameter than the moving plates. The central hole *i*

through the fixed plates is slightly larger than the corresponding metal central of the moving plates. The diameter *k* of the peripheral edges of the slots between the tongues *g* of the fixed element is slightly 60 greater than the overall diameter of the moving plates.

The condenser *e* is actuated by the spindle *m* and the latter is geared through the wheel *n* fast on the spindle, the wheel *o* on a spindle having the wheel *p* thereon, and the pinion *q* to the sleeve *r* which carries the moving plates of the condenser *f*. The said gearing provides that the moving plates *d* of the condenser *f* turn through several complete revolutions during a half turn of the moving plates *b* of the condenser *e*.

70 By reason of the construction of the plates *c* and *d*, one turn of the plates *c* causes the capacity of the condenser *f* to be changed 75 from minimum to maximum 12 times. If the gear ratio between the condensers be 1 to 12, then for one half turn of the condenser *e*, the condenser *f* will change in capacity 80 from minimum to maximum 72 times. 85 With this arrangement therefore it is possible to obtain an approximately accurate tuning of the two condensers by the operation of one control element which may be on the spindle *m* or on the sleeve *r*. A knob *s* and finger *t* moving over a dial *u* are shown on the sleeve *r*.

85 The insulating arrangements of the condensers have not been described as they are usual in character. The gearing between 90 the condensers may be made of vulcanite or like insulating composition.

Instead of being in the form of plates, the fixed and moving elements of the condenser *f* may be in the form of co-axial 95 tubes with longitudinal slots and tongues.

The number of slots and tongues in the moving and fixed plates may be varied to suit requirements.

What I claim is:—

100 1. In the combination of two variable condensers arranged in coaxial alignment, a shaft on which said condensers are mounted, the stationary and movable plates of one condenser being each provided with a plurality 105 of similar tongues and slots whereby the capacity is varied from minimum to maximum a plurality of times for a rotation of 180°, the other condenser being provided with fixed and movable plates providing a 110 change from minimum to maximum for a

rotation of 180°, and means on said shaft connecting both sets of movable plates for rotating one from the other.

2. In the combination of two variable condensers arranged in coaxial alignment, a shaft on which said condensers are mounted, the stationary and movable plates of one condenser being each provided with a plurality of similar tongues and slots whereby 10 the capacity is varied from minimum to maximum a plurality of times for a rotation

of 180°, the other condenser being provided with fixed and movable plates providing a change from minimum to maximum for a rotation of 180°, and means on said shaft 15 connecting both sets of movable plates, to cause a small motion of one set to be transmitted into a large rotation of the other set.

In testimony whereof I have signed my name to this specification.

RALPH LEONARD ASPDEN.
